UNITED STATES PATENT OFFICE.

JOSEPH L. BABER, OF WYNDAL, WEST VIRGINIA.

COUNTER PAPER-CUTTER.

1,040,845.

Specification of Letters Patent. Patented Oct. 8, 1912.

Application filed January 23, 1912. Serial No. 672,807.

To all whom it may concern:

Be it known that I, JOSEPH L. BABER, a citizen of the United States, residing at Wyndal, in the county of Fayette and State 5 of West Virginia, have invented new and useful Improvements in Counter Paper-Cutters, of which the following is a specification.

The present invention relates to improvements in paper severing or cutting devices 10 for store counters.

In carrying out my invention it is my purpose to provide a roll of paper arranged directly beneath the counter and a cutting 15 element which is sustained in a plane substantially parallel with the top of the counter; means being also provided whereby the severed end of the paper may be readily grasped by the attendant to draw a sufficient 20 quantity from the roll and to sever the same upon the knife without interfering with articles upon the counter. I also aim to provide a device of this class which will occupy a comparatively small space upon a counter 25 and which will permit of articles being moved therefrom without being interfered with by either the knife or the paper, the knife being also so arranged as to permit of the hand of the attendant or others contacting 30 the same without danger of injury.

A still further object of the invention is to provide novel and effective carriages for supporting the paper roll to assist in feeding the paper between a space formed between 35 the cutting element and an apron or guide arranged adjacent the cutting element.

A still further object of the invention is to provide the guide or apron with a centrally arranged depressed or recessed portion 40 whereby the severed edge of the paper, which is arranged directly below the cutting edge of the knife, may be grasped by merely passing the thumb of the operator within the said depression so as to permit any 45 quantity of the paper being withdrawn from the roll and severed.

A still further object of the invention is to provide a counter with a frame which has its upper portion arranged in a plane 50 with the top of the counter, the frame embodying depending sides having vertically arranged depressions forming ways and being further provided with slots which enter the ways, arranged within each of the 55 ways is a spring sustaining carriage, each of the said carriages having inclined slots,

the mouths of which being normally sustained away from the slots of the sides which communicate with the ways, each of the carriages being provided with suitable 60 ring members which are adapted to be grasped by the operator to bring the carriages into register with the slots of the sides, and whereby the trunnions of the paper roll may be passed through the slots 65 of the sides and journaled upon the lower walls provided by the inclined slots of the carriages, and, when pressure is released from the carriages, to permit of the said carriages being elevated by their springs to bring the slots thereof out of register with the slots of the sides of the frame, the papers upon the roll being so arranged that when a portion thereof is withdrawn to be severed from the roll the trunnions for the 70 roll will be forced away from the open mouth provided by the slots of the carriages. 75

A still further object of the invention is to provide, in a device of the class set forth a substantially curved knife which is arranged adjacent the guide member with simple and effective means for regulating the space of the cutting edge of the knife with relation to the guide. 80

With the above objects in view and others of a similar nature, the invention resides in the novel construction, combination and operative arrangement of parts, set forth in and falling within the scope of the appended 85 claims. 90

For the purpose of explaining the invention, the accompanying drawings illustrate a satisfactory reduction of the same to practice, but the important instrumentalities thereof may be varied and so it is to be 95 understood that the invention is not limited to the specific arrangement and organization shown and described.

In the drawings, Figure 1 is a perspective view of my improvement arranged upon a counter. Fig. 2 is a central longitudinal sectional view of the same. Fig. 3 is a sectional view upon the line 3-3 of Fig. 2. Fig. 4 is a sectional view upon the line 4-4 of Fig. 3. Fig. 5 is a front elevation of the frame removed from the counter. Fig. 6 is a detail perspective view of one of the ends of the counter removed and showing one of the carriages positioned thereon. Fig. 7 is a perspective view of the top of the frame 100 and looking toward the bottom thereof. Fig. 8 is a detail perspective view of the 105

110

knife member. Fig. 9 is a similar view of the guide or apron.

As is well known to merchants, it is desirable that their counters should be kept clear from all obstructions in order that the clerk or clerks waiting upon customers may have free access to all portions of the counter, the space upon the counter being required for the reception of articles until the same can be removed for delivery to the customer. Furthermore it is desirable that the wrapping paper for the article sold should be readily accessible to the clerk. In the device for holding the wrapping paper now most commonly employed, a frame is secured upon the top of the counter which is provided with bearings for the trunnions of the core upon which the paper is wound. While such devices may be considered ornamental they are a source of great inconvenience to the clerks owing to the fact that the space occupied by the same is needed for other purposes. The said racks are also generally arranged adjacent one end of the counter so that a clerk serving a person at the opposite end of the counter is forced to travel a considerable distance in order to obtain paper with which to wrap the articles. It is the primary object of my invention to provide means arranged level with the top of the counter whereby a sufficient quantity of paper may be withdrawn from a roll which has its core mounted in trunnions below the top of the counter and wherein a sufficient amount of paper may be withdrawn from the roll by the simple passage of the thumb of the clerk over the cutting element which is arranged as stated in a plane with the counter, and after a sufficient quantity of paper has been unrolled the same may be readily severed from the remainder of the roll and the edge of the said paper arranged directly below the cutting element and in a position to be drawn over the counter when additional paper is required.

Referring now to the drawings in detail the numeral 1 designates an ordinary counter. The counter 1 has its upper portion or face provided with a rectangular opening and the under face of the counter adjacent the front and rear portions thereof are provided with cleats 2, which is adapted to serve as a support for the top member 3 of the frame 4. This top 3 is of the shape corresponding with the openings in the counter, and the said top 3 is also of a thickness equaling that of the boards from which the counter is constructed so that when the frame is arranged upon the counter a smooth unbroken surface is presented. The top 3 is provided with longitudinally extending slit or opening 5, the under face of the said top is provided with a curved or inclined wall 6 which communicates with the slit,

while the opposite wall by the said slit is tapered to a point which is disposed approximately central of the curved wall 6. The numeral 7 designates an apron which is received within a depression provided upon a top, as well as upon the upper face of the tapered wall or edge. The longitudinal wall or edge provided by the rectangular depression and adjacent the inclined or curved wall formed by the slit, is depressed or recessed to receive one of the longitudinal edges of a curved cutting element 8. This cutting element 8 is formed adjacent its opposite end with openings having their upper portions reamed, and the said openings are adapted to receive the beveled heads of securing threaded elements 9, the cutting edge of the member 8 is arranged a slight distance away from the substantially vertical wall of the apron or guide, and the elements 9 are adapted to regulate the distance between the said cutting edge and the said guide. The apron 7 is centrally provided with a depressed portion 10, the said portion being of a size sufficient to receive the thumb of the clerk, and for a purpose which will be presently set forth.

The top 3 of the frame is provided adjacent its opposite ends with dove-tailed recesses 11, the said recesses being adapted to receive the dove-tailed tongues 12 provided upon the side members 13 and 14 of the frame. Each of the sides 13 and 14 is provided with a vertically disposed centrally arranged depression 15 each of which is adapted to serve as a way for a carriage which will be presently described. The inner faces of each of the sides 13 and 14 is also provided with a passage 16, the same communicating with the way 15 upon each of the sides.

The dove-tailed portions 12 of the sides 13 and 14 are preferably centrally cutaway in a plane with the side walls provided by the ways 15, arranged within the said cutaway portions are rods 17. Each of these rods 17 is adapted to receive one of the end convolutions of the helical spring 18, the opposite end convolution engaging within an eye 19 formed upon a carriage 20. The carriages 20 are of a width sufficient to snugly engage within the ways 15, and the spring members are adapted to force the said carriages upwardly toward the top of the frame. The lower extremity of each of the carriages is provided with a downwardly extending stem 21, whereby each carriage may be retracted against the pressure of its spring. Each of the carriages has its face adjacent that of the passage 16, formed with an inclined slot 125 or depression 22, the said depressed portions being adapted to serve as journals for trunnions 23 provided upon a core 24 around which is wound a roll of paper 25. In positioning the roll of paper upon the device, the

end of the paper is first fed between the apron and the knife and the carriages are forced downwardly against the pressure of their springs until their recessed portions 5 are brought into register with the passages 16, the trunnions of the core being passed from the said passages until they are received within the depressions of the carriages. When pressure is released from the 10 carriages the springs of the carriages will cause the same to travel upwardly in their notched or recessed portions away from the passages 16, so that the trunnions of the core cannot become accidentally removed from 15 their bearings.

By references to the several figures of the drawings it will be noted that the depressed or notched portion on each of the carriages has its walls inclined downwardly which 20 also assists in preventing the accidental removal of the trunnions. It will be further noted that the roll of paper will be normally forced toward the under face of the top 3 of frame, but the pressure is not sufficient to 25 prevent the ready unwinding of the paper from the roll.

In operation, the clerk merely draws his thumb over the curved knife and within the centrally arranged depression provided by 30 the guide or apron, when his thumb will contact with the edge of the paper which has been severed by the knife, the said contact being sufficient to draw the paper over the apron and below the cutting end of the 35 knife. When a desired quantity of paper has been unrolled the clerk grasping the paper brings the same against the sharpened edge of the knife, which leaves the edge of the paper upon the roll directly below the 40 knife and in a position to be again contacted when more paper is desired. In this connection it may be stated that the resilient cutting element 8 exerts a sufficient tension upon the paper as to retain the edge thereof 45 against the apron 7, even after a portion of the said paper has been severed.

Having thus described the invention what I claim is:—

1. A counter paper cutter embodying a

frame including depending sides, said sides 50 being provided with vertically arranged ways, a paper roll supporting carriage within the ways, resilient members supporting the carriages, the top of the frame being provided with a longitudinally extending 55 depression, one of the walls provided by the depression being rounded from the lower face of the top toward the upper face thereof, the adjacent wall being tapered to a point which is arranged approximately central of the rounded wall, an apron upon the upper face of the top and upon the upper face of the tapered wall, the top being provided with an annularly arranged depressed portion, a cutting element comprising a flat 60 member which is received within the recess, and a rounded cutting edge which is arranged adjacent the apron, the said apron adapted to receive and guide the paper from the roll and means for adjustably sustaining 65 the cutting member against the paper upon the apron.

2. In a device for the purpose set forth, the combination with a counter having an opening, of cleats partially closing the opening, a rectangular frame supported upon the cleats and having its top portion arranged in a plane with the counter, the said top having a centrally arranged longitudinally extending slit, an apron for one of the 75 walls provided by the slits, a knife co-acting with the apron, means for adjusting the knife with relation to the apron, the side members of the frame being provided with ways, carriages within the ways, a spring 80 member supporting each of the carriages, each of said carriages being provided with a depending stem, a paper roll having its core trunnioned upon the carriages, and the paper from the roll adapted to be fed upon 85 the apron and to be contacted by the knife substantially as described.

In testimony whereof I affix my signature in presence of two witnesses.

JOSEPH L. BABER.
